UNITED STATES PATENT OFFICE.

JOHN A. ANDERSON, OF AUSTIN, MINNESOTA.

BAG-HOLDER.

SPECIFICATION forming part of Letters Patent No. 625,134, dated May 16, 1899.

Application filed September 12, 1898. Serial No. 690,749. (No model.)

To all whom it may concern:

Be it known that I, JOHN A. ANDERSON, a citizen of the United States, residing at Austin, in the county of Mower and State of Minnesota, have invented certain new and useful Improvements in Bag-Holders, of which the following is a specification.

This invention relates to bag-holders, and particularly to the class of grain-bag holders.

10 The object of the invention is to provide an improved novel device for holding grain or other bags for filling of peculiar construction and arrangement of parts.

15 The invention consists in the novel construction, arrangement, and combination of parts.

20 In the accompanying drawings, forming part of this application, Figure 1 is a perspective view of the device holding a bag open. Fig. 2 is a perspective view of one of the arms and its pivot-plate.

25 The same numeral references denote the same parts throughout both figures of the drawings.

30 The hanger consists of an angle-iron 1, having hooks 2 on the vertical portion to engage a wall-bracket or projection 3 or other suitable object to suspend the same, though the said hooks may be dispensed with and the hanger secured in place in any desirable manner.

35 L-shaped plates 4 are secured to the horizontal portion of the hanger 1 by means of pivots 5, extending through the long arm of the plates and through the said hanger. The short arm of the pivot-plates depends over the front edge of the hanger and has one end of the bag-stretcher arms 6 secured thereto. These arms are of thin metal, so as to give them sufficient flexibility to form a semicircle when holding a bag and be relaxed out of such curve when disengaged with the bag, and the other ends of said arms have curved or inturned free ends.

40 Owing to the angular shape of the hanger-iron, the vertical portion thereof forms a rigid back for suspension and the horizontal portion thereof a projecting base or bed upon which the long arm of the L-shaped plates works on pivots. The short arm of said plates extends below the said horizontal portion, at right angles thereto, so that there is no vertical spring or tendency of the parts to sag in

holding a bag, but the latter takes around the depending portions of the plates close up to the hanger without engaging it.

55 At the intersection of the long and short arms of the pivot-plates are lugs or projections 7, which carry a spiral spring 8, the ends of the latter being secured to the said plates.

60 The hanger 1 is provided with vertical stoppins 9, which control the outward movement of the pivot-plates, the inward movement of said plates being controlled by the spring 8.

65 By reference to Fig. 1 it will be seen that owing to the peculiar shape, spring tension, and flexibility of the arms the mouth of the bag is stretched into semicircular form, leaving the front edge of the bag-mouth practically straight and well drawn, which is a great 70 advantage in bag or sack filling.

75 It is obvious that the spring has only to be compressed to shorten the reach of the stretcher-arms in order to insert them in the mouth of a bag, whereupon the spring is allowed to expand and force the pivot-plates apart, and thereby extend the reach of the arms and stretch the bag open, as clearly shown in Fig. 1.

80 Although I have shown the pivot-plates and arms made separate and the lugs or projections riveted in place, all of these parts may be made in one and the same piece.

85 Having thus described my invention, what I claim as new, and desire to secure by Letters Patent, is—

90 1. In a bag-holder, the combination, with the angle-iron forming a hanger, and having means for suspending it, and the vertical stop-pins on the hanger, of the spring-controlled plates pivoted to and depending at right angles from the hanger, to permit the bag-mouth to take around the depending parts of said plates without engaging the hanger, and the flexible stretcher-arms secured to the said depending parts, and adapted to be bent in a curve from one end to the other when holding a bag and relaxed out of such curve when disengaged with the bag, substantially as set forth.

95 2. In a bag-holder, the combination, with the hanger comprising vertical and horizontal portions, means on the vertical portion to suspend the hanger, and vertical stop-pins on

the horizontal portion, of the L-shaped plates pivoted at one end on the horizontal portion between the stop-pins, the other end of said plates depending at right angles from the 5 front edge of said horizontal portion, and controlled in their outward movement by said pins, a spring between the depending ends to control the inward movement, and the flexible stretcher-arms having one end se-

cured to the said depending ends, and the other end left free and curved inward, substantially as set forth.

In witness whereof I hereunto set my hand in the presence of two witnesses.

JOHN A. ANDERSON.
